UNITED STATES PATENT OFFICE.

EUGENE APPEL, OF LOS ANGELES, CALIFORNIA.

WATER SERVICE.

Application filed September 8, 1921. Serial No. 499,135.

To all whom it may concern:

Be it known that I, EUGENE APPEL, a citizen of the United States, residing at Los Angeles, in the county of Los Angeles and State of California, have invented new and useful Improvements in a Water Service, of which the following is a specification.

My invention relates to water services, and consists of the novel features herein shown, described and claimed.

It is usual to deliver drinking water in large glass bottles and my object is to make an improved service for mounting the bottle bottom upwards so that the water may be drawn into drinking cup at will.

In the drawings:

Figure 1 is a fragmentary sectional and side elevation of a complete water service, ready for use and made in accordance with the principles of my invention.

Figure 2 is a horizontal sectional detail on the line 2—2 of Figure 1.

Figure 3 is an enlarged fragmentary sectional detail on the same plan as Figure 1, and showing a modified construction of the gasket and closure.

Figure 4 is a fragmentary sectional detail on the same plans as Figures 1 and 3, and showing a modified construction of the bottle closure, the closure in Figure 1 being porcelain or the like, the closure in Figure 3 being cast brass or the like, and the closure in Figure 4 being sheet metal.

Referring to the drawings in detail:

The water container is a glass bottle, (1) of the usual form and construction and has a mouth (2) leading through a mouth portion (3) having a tapered outer face (4) and an edge (5). The soft rubber gasket (6) fits tightly upon the face (4) and against the edge (5) and has an opening (7) in line with the opening (2).

The closure (8) is made of porcelain or the like and consists of a socket (9) having an inner bevelled face (10) fitting tightly against the gasket (6) in opposition to the face (4) and a shoulder (11) pressing the gasket (6) against the edge (5) and a cap-shaped head (12) forming a chamber (13) extending downwardly from the shoulder (11) and includes a straight annular wall (14). The spigot (15) is fixed through the wall (14) and leads from the chamber (13).

The vent pipe (16) is fixed through the annular wall (14) and extends through the

chamber (13), through the opening (7), through the mouth (2) and through the chamber (17) of the bottle (1) to the air space (18), so that as the water is drawn out through the spigot (15), air will pass 60 through the vent pipe (16) to the air space (18) to relieve the vacuum, and of course the air space will enlarge as the water is drawn out.

The table (19) may be any suitable flat 65 topped support. The stand (20) rests upon the table (19) and supports the bottle (1). The shelf (21) is flat and has a circular out edge (22) extending through more than two-thirds of a circle and has a cut-away portion 70 (23) between the ends of the circular edge (22). The legs (24—25 and 26) are evenly spaced apart against the edge (22) and secured in place by screws (27), the table (21) being near the lower ends of the legs, 75 and a spring hoop (28) is placed around the legs near their upper ends and secured by nails or screws (29) and the end faces (30) of the legs are bevelled inwardly to fit the bevelled shoulders (31) of the bottle 80 (1). When the cap (12) is upon the table (21) the shoulder (31) is upon the faces (30). The hoop (28) will spring more or less to allow sufficient weight to press the closure (8) against the mouth piece (3) and 85 hold the water.

The bottle (1) is brought in right side up, the cork removed, the closure (8) applied, and the whole is placed in position upon the stand (20) with the spigot (15) in 90 line with the cut-away place (23) so that the cup (32) may be placed under the spigot.

The water service thus constructed is cheap and simple and at the same time effective and satisfactory.

In the modification shown in Figure 3 the closure (33) is cast brass or the like and the gasket (34) fits upon the shoulder (35) only.

In the modification shown in Figure 4, the 100 closure (36) is of sheet metal and the gasket (34) may be used as shown or the gasket (6) may be used.

Various changes may be made without departing from the spirit of my invention 105 as claimed.

I claim as my invention:

1. A water service comprising a table, yielding legs supporting the table and extending upwardly from the table and hav- 110

ing bearing faces at their upper ends, and a closure resting upon the table and having a spigot and vent pipe, so that a water bottle will fit the closure and bearing faces, with 5 the vent pipe extending into the bottle.

2. A water service comprising a table, yielding legs supporting the table and extending upwardly from the table and having bearing faces at their upper ends, said table 10 being near the lower ends of the legs, a spring hoop secured around the legs near their upper ends, and a closure resting upon the table and having a spigot and vent pipe, so that when a water bottle is applied the 15 bearing faces will yield to allow the bottle to fit the closure.

3. A water service comprising a circular table having a cut-away portion extending from the circular edge, legs evenly spaced apart, and having their lower portions secured against the edge of the table, a spring 20 hoop secured around the legs near their upper ends, and a closure resting upon the table and having a spigot in line with the cut away portion, and having a vent pipe, 25 so that a water bottle may be brought in right side up and the service applied and inverted upon a supporting table, the bearing faces yielding enough to allow the bottle to fit the closure.

EUGENE APPEL.
